UNITED STATES PATENT OFFICE.

WALTER G. E. ROLAFF, OF ST. LOUIS, MISSOURI.

DISTRIBUTOR FOR USE IN REFRIGERATING SYSTEMS.

Application filed January 10, 1924. Serial No. 685,470.

This invention relates to refrigerating machines, and has for its general object the provision of a distributor for the refrigerant to be used in the system in place of the 5 ordinary expansion valve.

A further object of the invention relates to the novel construction of the distributor, including the provision of means for maintaining the pressure in the distributor at a 10 point sufficiently lower than the pressure in the condenser to permit the ready flow of the refrigerant through the distributor.

Still further objects of the invention relate to a novel combination of elements constituting a refrigerating system, as a whole, resulting from the incorporation in such system of my improved distributing device.

The invention is illustrated in the accompanying drawings, in which—

20 Figure 1 is a sectional view illustrating my improved refrigerant distributor as constructed for use on the high pressure side of a refrigerating system; and

25 Figure 2 is a diagrammatic view illustrating a refrigerating system having my distributor embodied therein.

In order that the relation of my invention to a refrigerating system, and the advantages to be derived from its use, may be 30 better understood, I will first state briefly the disadvantages in prior arrangements which it is the main purpose of the present invention to overcome.

As stated above, my distributor is 35 designed to replace the ordinary automatic expansion valve, which, in one form or another, has heretofore been used in practically all mechanical refrigerating systems. The expansion valve employs a diaphragm which, 40 in all installations of which I am aware, is so located in the system as to be susceptible to changes in pressure on the low side of the system. This diaphragm ordinarily works a needle valve, so that when the pressure 45 on the low side reaches a certain point, the diaphragm is depressed against a spring and the valve is closed, shutting off the flow of the refrigerant. An adjustment of the spring makes it possible to set the expansion 50 valve to work at any given pressure.

The expansion valve, as so used, has two pronounced disadvantages. The first of these is its inability to adapt itself to varying changes of temperature to produce the 55 highest refrigerating efficiency in operation.

To make this clear, it should be understood that, for any given temperature in the chamber or enclosure cooled, for example, an icebox, there is a corresponding pressure at which the liquid refrigerant will be capable 60 of absorbing the largest quantity of heat. To obtain the best possible results from an expansion valve, therefore, it should, theoretically, be adjusted every minute of the day to operate at that pressure which will 65 ideally correspond to the temperature in the expansion coil. Such frequent adjustment is, of course, wholly impracticable. In practice, therefore, the valve is simply set to operate at a given pressure. As a result, 70 there is only one temperature in the expansion coil for which such setting is ideal. To the extent that the temperature fluctuates above or below that point, the system will 75 decrease in efficiency.

The second disadvantage of the expansion valve is that it cannot prevent the flow of gas from the compressor to the expansion coil. When all the liquid has been passed over into the low side, gas will be permitted 80 to go over from time to time. This, of course, impairs the efficiency of the system, since the gas has only a fraction of the refrigerating ability that is possessed by the liquid.

To overcome the above disadvantage, I provide a distributor in which is always constantly maintained a body of liquid refrigerant, which effectually prevents any gas, that may have escaped condensation in the condenser, from reaching the valve and, therefore, from going over into the low side. This distributor is operated by the flow of the liquid refrigerant and it is entirely independent of the pressure on the low side. 90 This pressure, therefore, since it is not throttled by the distributor, as it would be with an expansion valve, will automatically respond to changes of temperature in the expansion coil, so that whatever the temperature, the pressure will always be at the ideal point for maximum absorption of heat.

I will now describe the invention in detail, referring to the accompanying drawing, in which the numeral 1 (Figure 2) indicates, 105 conventionally, a compressor from which a pipe 2 leads to a condenser 3, which communicates with a receiver 4 for the liquid refrigerant. From this receiver, a pipe 5 leads to my improved distributing device 6, 110

and from this distributor a pipe 7 leads to the bottom of an expansion coil 8 which, in practice, is located in the ice-box or other enclosure to be cooled. From the top of the 5 expansion coil, a pipe 9 leads back to the suction side of the compressor.

Referring now to Figure 1, where the distributor is shown on an enlarged scale, the 10 numeral 10 indicates the casing of the distributor, into the bottom of which, at one end, leads the pipe 5, and, at the other end, the pipe 7, previously referred to.

The casing 10 provides a chamber 11, and located within this chamber is a float valve 15 comprising a hollow float 12, having at one end an arm 13, which is pivotally mounted at 14 in the upper bifurcated extension 15 of a valve block 16, mounted on a raised portion 17, provided on the bottom of the 20 casing 10. Pivotally mounted on the arm 13 between the pivot 14 and the float 12 is a needle valve 18, which works in and is guided by a recess 19 in the valve block 16, and, at its lower end, cooperates with a valve 25 seat 20 in the bottom of the valve block. A port 21 leads through the valve block to the recess 19 to permit the flow of liquid refrigerant from the chamber 11 to the recess 19, and thence through the opening in 30 the valve seat 20 when the valve 18 is raised.

In the operation of the device as thus far described, the liquid refrigerant passes through the pipe 5 into the chamber 11 of the distributor, and when it reaches a certain 35 height therein, will raise the float 12, which will operate to lift the needle valve 18 from its seat and permit the liquid refrigerant to pass through the pipe 7 to the expansion coil 8. The needle valve, therefore, will open only when there is a sufficient 40 quantity of liquid in the distributor to raise the float to which the valve is attached. Therefore, there is constantly maintained in the chamber 11 a body of liquid refrigerant, 45 and this, as stated above, will prevent passage of any gas, that may have escaped condensation in the condenser 3, from reaching the needle valve and passing over into the low side of the system. In this way, the 50 disadvantage, as respects the passage of gas to the low side, which obtains in the use of an expansion valve, as above alluded to, is overcome.

Again, my distributor works on the principle of the flooded system. It operates to 55 always maintain a certain quantity of liquid in the expansion coil 8. As fast as the refrigerant gasifies, it is compressed, condensed, and, in the form of liquid, again 60 passed through the distributor into the expansion coil. This flow of liquid, as will be obvious, is entirely independent of the pressure on the low side; and this pressure will automatically respond to changes in temperature, so that whatever the temperature

at the expansion coil, the pressure will always be at the ideal point for maximum expansion.

As thus far described, the refrigerating system, including the distributor, would 70 only operate in installations in which the distributor 6 is located below the condenser. For obvious reasons, the distributor should be placed as close as possible to the expansion coil 8, and since, in most commercial 75 installations, the expansion coil is located above the compressor 1, the distributor will also be above the compressor. In practice, it has been found that the liquid refrigerant will not flow from the condenser upward 80 into the distributor, for the reason that the pressure in the distributor is exactly the same as the pressure in the condenser case.

To overcome this obstacle, I provide a gas relief tube for maintaining the pressure in 85 the distributor at a point sufficiently lower than the pressure in the condenser to permit the upward travel of the refrigerant. This tube is indicated in the drawing by the numeral 22 and, as shown, leads from near the 90 top of chamber 11 through the valve block 16 and into communication with the pipe 7, or low side of the system. The tube 22 furnishes an avenue of escape for the gas that is generated at the surface of the liquid in 95 the distributor, such gas being short-circuited past the valve into the low side pipe. It should be understood, however, that the only gas that escapes through the tube 22 is the gas generated in the distributor itself, which 100 is very minute in quantity and not sufficient to noticeably impair the efficiency of the system when such gas is permitted to escape into the low side. In other words, none of the gas that has escaped condensation in 105 the condenser ever reaches the relief tube 22, because it is prevented from doing so by the body of liquid that is always maintained in the bottom portion of the distributor.

It should be stated, in conclusion, that the 110 position of the parts of the system, as illustrated in Figure 1, is merely for convenience of illustration, and does not necessarily represent the relative arrangement of the parts of the system as would obtain in actual 115 practice. Also, while I have illustrated, and prefer to use, a float valve for automatically controlling the flow of the refrigerant to the expansion coil, the invention, in its broad aspects, is not limited to the use of such a 120 valve.

I claim:

1. In a refrigerating system, involving a compressor, condenser and expansion coil, a distributor located between the condenser and expansion coil and comprising a chamber communicating with the condenser and having a valve-controlled outlet leading to the expansion coil, a float in said chamber connected with said valve and acting to con- 125
- 130

- trol the same according to the rise and fall of the liquid refrigerant in said chamber, and means for by-passing gas from said chamber around said valve to the low side 5 of the system.
2. In a refrigerating system, involving a compressor, condenser and expansion coil, a distributor located between the condenser and expansion coil and comprising a chamber 10 communicating with the condenser and having a valve-controlled outlet, and a gas-escape tube leading from near the top of said chamber around said valve to the outlet to the expansion coil for by-passing gas 15 from said chamber to the low side of the system.
3. In a refrigerating system, involving a compressor, condenser and expansion coil, a distributor located between the condenser 20 and expansion coil and comprising a chamber communicating with the condenser and having a valve-controlled outlet leading to the expansion coil, means for automatically regulating the passage of liquid from said 25 chamber to the expansion coil through the medium of the quantitative flow of the liquid refrigerant from the condenser into said chamber, and means for by-passing vaporized gas from said chamber around said 30 valve to the low side of the system.
4. In a refrigerating system involving a compressor, condenser and expansion coil, a distributor for liquid refrigerant located between the condenser and expansion coil comprising a chamber communicating with the 35
- condenser and having a valve-controlled outlet leading to the expansion coil, and means for maintaining the pressure in said chamber below the pressure in the condenser.
5. In a refrigerating system involving a 40 compressor, condenser and expansion coil, a distributor for liquid refrigerant located between the condenser and expansion coil comprising a chamber communicating with the condenser and having an outlet leading 45 to the expansion coil, an automatic valve for controlling the flow of liquid refrigerant from said chamber to the expansion coil, and means for maintaining the pressure in said chamber below the pressure in the con- 50 denser.
6. In a refrigerating system involving a 55 compressor, condenser and expansion coil, a distributor for liquid refrigerant located between the condenser and expansion coil comprising a chamber communicating with the condenser and having a valve-controlled outlet leading to the expansion coil, and means affording constant communication between the interior of said chamber above the 60 level of the liquid refrigerant therein and said expansion coil for by-passing gas from said chamber around said valve to the low side of the system, whereby to maintain the pressure in said chamber below the pressure 65 in the condenser.

In testimony whereof, I have hereunto set my hand.

WALTER G. E. ROLAFF.
